UNITED STATES PATENT OFFICE.

ALEXANDER K. SUTHERLAND, OF NEW BRITAIN, CONNECTICUT, ASSIGNOR TO THE TRUMBULL ELECTRIC MFG. CO., OF PLAINVILLE, CONNECTICUT, A CORPORATION OF CONNECTICUT.

INCLOSED SWITCH.

1,288,740.

Specification of Letters Patent. Patented Dec. 24, 1918.

Application filed March 29, 1918. Serial No. 225,446.

To all whom it may concern:

Be it known that I, ALEXANDER K. SUTHERLAND, a subject of the King of Great Britain, residing at New Britain, Connecticut, cut, have invented a new and useful Inclosed Switch, of which the following is a specification.

My present invention, as the title indicates, has reference to switches of the 10 closed or so-called "safety" type, the general objects of the invention being to provide a switch of this character which will be relatively inexpensive and which at the same 15 time will be positive and certain in its operation.

Another important object is to provide 20 automatic locking means for securing the cover closed when the switch is closed and for locking the switch open when the cover 25 is open which will be simple, compact and not liable to get out of order.

In the accomplishment of the foregoing 30 and other objects, as will later appear, I employ a single locking member substantially 25 in the form of a plate pivoted to rock into holding engagement with a locking shoulder carried by the operating handle and adapted to be released from said locking shoulder by a stop on the cover, said locking plate being 35 held interlocked with the cover stop when the cover is closed by means of a cam element also carried by the operating handle.

Other features of the invention and 40 details of construction will appear as the specification proceeds.

The accompanying drawing illustrates 45 the invention as embodied in a practical commercial form, it being understood, however, that various changes and modifications 50 may be made without departure from the true spirit and scope of the invention.

In said drawing:

Figure 1 is a front view looking into an 55 opened switch box having the invention incorporated therein, the switch in this case being locked in the open circuit position.

Fig. 2 is a sectional view taken substantially 60 on the plane of the line 2-3 of Fig. 1 and indicating the locking parts in the 50 position just described.

Fig. 3 is a similar sectional view on the line 2-3 showing the cover locked closed and the switch free to be operated.

Fig. 4 is a cross sectional view of the handle construction.

The switch box or casing 5 is shown as 55 made of sheet metal and provided with a hinged cover 6, as common in this art. The switch 7 which is mounted in the box may be of any approved construction and is 60 shown as of the type disclosed in Patent No. 1,254,067 having a movable switch element 8 pivoted on the center 9.

10 designates the switch operating member shown in the form of a handle journaled 65 in the side wall of the box on a center corresponding to the pivotal center of the movable switch element.

A preferred form of mounting for the 70 switch handle is shown in detail in Fig. 4, 75 the same consisting of a bearing disk 11 which is rotatably seated in a journal opening 12 provided therefor in the wall of the box, said bearing disk being of slightly thicker metal than the wall of the box, the 80 handle 10 being secured to the outer face of this bearing disk, and a plate 13 being secured to the inner face of said bearing disk, said handle and plate having portions extending beyond the rim of the bearing 85 disk so as to constitute abutments limiting the lateral shifting movement of the bearing disk in the journal opening. These parts may be secured together as by means of rivets 14 passed therethrough and there 90 is shown a bracket 15 secured to the inner face of the plate 13, which bracket forms the operating connection between the handle and the movable switch element.

The plate 13 which is carried by and in 95 effect forms a part of the operating handle is what I have termed a cam or locking plate, it having as shown, an abrupt locking shoulder 16 and a raised cam track 17 at one side of said locking shoulder.

18 designates the locking member which in the construction illustrated is in the nature of a hook pivoted at 19 and having a stop shoulder 20 for engagement with the locking shoulder of the handle.

At the opposite side of the pivotal center 19 the locking member is slotted or forked to provide an abutment or jaw 21 and spaced above that a securing or holding projection 5 or jaw 22, said upper securing jaw 22 being shown somewhat shorter than the lower abutment jaw 21, and the face of the abutment jaw being inclined somewhat on a downward slant from the outer or free end 10 thereof.

Mounted on the cover in position to engage this lower inclined jaw is a stop or projection 23, shown in the form of an inwardly projecting pin carried by the dependent 15 flange 24 of the cover. The edge of the box wall is slotted as indicated at 25 to admit this stop pin.

The locking plate is shown as acted upon by a spring 26 which rocks the plate forwardly to hold the hook portion of the plate either engaged with the locking shoulder of the handle as indicated in Fig. 2, or bearing upon the cam face 17 as indicated in Fig. 3. In the first condition referred to the switch 20 is open and is locked in this open position by reason of engagement of the hook of the locking plate with the locking shoulder carried by the handle. In this forwardly rocked condition of the locking plate the upper cover securing jaw 22 is free of the locking pin on the cover, and the cover is then freed from the control of the automatic locking mechanism. When the cover is closed, as shown in Fig. 3, the locking pin on the 25 cover strikes the inclined face of the lower abutment jaw and rocks the locking plate in a direction to free the hook thereon from engagement with the locking shoulder of the handle. In the course of this movement, it will be noted that the securing jaw 30 becomes engaged over the top of the locking pin. The switch is now free to be shifted to closed circuit position. As soon as the switch handle is rocked forwardly to close 40 the circuit, the cam track 17 is brought beneath the nose of the locking plate, and then acts as an abutment to prevent said locking plate from rocking forwardly so as to release the cover. This cam track thus operates to hold the locking plate in securing 45 engagement with the stop on the cover so long as the switch is in closed circuit position and up to the time that the switch has been fully opened.

The automatic locking mechanism disclosed will thus be seen to consist of but two main parts, the pivoted locking plate which is controlled by the cover, and the cam plate carried by the handle. Both these 50 parts are of simple construction and may be formed by simply stamping them from sheet metal.

The locking plate may be mounted in a small casing 27 secured to the inner face 60 of the box wall as by means of suitable fas-

tenings such as the rivets 28. The bottom wall of this casing may serve as an abutment for the spring 26. A light spring 29 is shown provided for holding the locking plate shifted over against the side wall of the box into the plane of the cam disk of the handle. The locking plate is further shown provided with an abutment lug to take the thrust of the spring, which lug, as plainly appears in Fig. 1, is angularly offset from the otherwise flat plane of the plate so as to provide room between the plate and the side of the box for the spring 26.

From the foregoing, the invention will be seen to possess many advantages in the way 80 of general simplicity, ruggedness of structure, etc., and it will be apparent furthermore that the locking operation of the device is positive and sure.

I claim:

1. In combination, a switch casing having a movable cover, a switch in said casing having a movable switch element, a switch operating member journaled in one wall of the casing and provided with a stop shoulder, 90 connections from said switch operating member to the movable switch element, a hook pivoted on the casing adjacent the operating lever and arranged to engage the stop shoulder aforesaid, said hook having a slot therein and the casing having a slot in the wall thereof coinciding with said slot, and a locking abutment on the cover arranged as the cover is closed to pass into the coinciding slots and rock the hook on its 100 pivot to cause the same to overlie and hold the locking abutment carried by the cover.

2. In combination, a switch casing having a movable cover, a switch in the casing having a movable switch element, an operating member journaled in one wall of the casing and operatively connected with the movable switch element, a cam carried by the switch operating member having a cam surface terminating in an abrupt locking shoulder, a hook pivotally supported on the casing bearing on the cam track and adapted to drop into engagement with the locking shoulder to hold the switch in open circuit position, and means on the movable cover for 110 engagement with the hook to rock the same out of engagement with the locking shoulder of the cam.

3. In combination, a switch casing having a movable cover, a switch in said casing, a movable switch operating member provided with a locking shoulder, a locking member provided with a stop shoulder for engagement with the locking shoulder to hold the switch operating member in a predetermined 120 position, a stop on the movable cover for engaging the locking member in the closing movement of the cover to shift said locking member and throw the stop shoulder thereon free of the locking shoulder, a securing pro 130

jection on the locking member positioned to make interlocking engagement with the stop on the cover, and a holding track actuated by the operating member to hold the locking member in position with the securing projection locked in engagement with the stop on the cover.

4. In an inclosed switch, a switch box having a movable cover, a switch in said box, a pivoted switch operating member connected with the switch, a locking shoulder carried by said pivoted operating member, a pivoted locking member having a portion for engagement with the locking shoulder, a projection on the movable cover for engagement with the locking member to rock the same out of holding engagement with the locking shoulder, means on said locking member for engagement with the projection on the cover when shifted thereby to secure said cover projection, and means carried by the switch operating member for holding the pivoted locking member in position securing the projection on the cover.

5. In an inclosed switch, a switch box having a movable cover, a switch in said box, a pivoted switch operating member provided with a locking shoulder, a pivoted locking member provided with a stop shoulder for engagement with the locking shoulder to hold the switch operating member in a predetermined position, a stop on the movable cover for engagement with the pivoted locking member to shift the same and throw the stop shoulder thereon out of engagement with the locking shoulder, a securing projection on the locking member arranged to be carried into securing engagement with the stop on the cover as the locking member is shifted by said stop, and a holding track on the operating member engageable with the locking member as said operating member is shifted after the release of the locking shoulder for holding the securing projection engaged with the stop on the cover.

6. In an inclosed switch, a switch box having a movable cover, a switch in said switch box, an operating handle journaled in the switch box, a locking shoulder carried by said operating handle and a cam track to one side of said locking shoulder, a locking member pivoted in the switch box having a stop shoulder for engagement with the locking shoulder, a stop on the movable cover engageable with the locking member to shift the stop shoulder thereon out of engagement with the locking shoulder and into position to be engaged by the holding cam when the operating handle is operated, and a securing projection on the locking member adapted to be engaged with the stop on the cover as said member is shifted by said stop and arranged

to be held engaged with said stop by the holding cam aforesaid.

7. In an inclosed switch, a switch box having a movable cover, a switch in said box, an operating handle journaled in the box and connected with the switch, a stop shoulder carried by said operating handle and a cam track at one side of said stop shoulder, a pivoted locking member having a stop shoulder at one side of the point of pivotal support for engagement with the locking shoulder, and spaced holding jaws at the opposite side of the center of pivotal support, and a stop on the cover engageable between said spaced holding jaws to rock the stop shoulder out of engagement with the locking shoulder, said locking member being engaged by the holding cam when the handle is then operated to hold the jaws aforesaid engaged with the stop on the cover.

8. In an inclosed switch, a switch box having a movable cover, a switch in said box, an operating handle journaled in the box and connected with the switch, a disk carried by said handle having a cam track terminating in an abrupt locking shoulder, a pivoted locking plate having a stop shoulder for engagement with the locking shoulder and a pair of spaced holding jaws, and a stop on the movable cover engageable with one of said jaws to rock said plate on its pivot and carry the stop shoulder out of engagement with the locking shoulder and the other jaw into position over the stop, said locking plate having a part engaged by the cam track when the handle is then operated to hold said last mentioned jaw engaged over the stop on the cover.

9. In an inclosed switch, a switch box having a slot cut in the edge of one of the side walls thereof and provided with a movable cover having a dependent flange to engage over said slotted portion of the side wall, an inwardly extending projection on said flange engaging in said slot as the cover is closed, a locking plate pivoted on said side wall of the box having a jaw extending across the slot therein to be engaged by the projection on the cover and a jaw above said first jaw to engage over the projection as said locking plate is rocked by the projection, a switch in the box, a handle journaled in said side wall of the box and connected with the switch, a cam plate carried by said handle having a cam track for holding the locking plate rocked into position engaged with the cover projection and an abrupt locking shoulder at the end of said cam track, and a stop shoulder on the locking plate for engagement with the locking shoulder.

ALEXANDER K. SUTHERLAND.
